UNITED STATES PATENT OFFICE.

JOHN CHARLIS COLLIER, OF GALVESTON, TEXAS.

DESIGN FOR AN INSECT-GUARD FOR FURNITURE.

SPECIFICATION forming part of Design No. 27,312, dated July 6, 1897.

Application filed May 22, 1897. Serial No. 637,791. Term of patent 14 years.

To all whom it may concern:

Be it known that I, JOHN CHARLIS COLLIER, a citizen of the United States, residing at Galveston, in the county of Galveston and State of Texas, have invented a new and original Design for an Insect-Guard for Furniture, of which the following is a specification.

This invention relates to a new and original design for an insect-guard for furniture; and it has for its object to provide a design of this character that shall be both useful and ornamental.

The leading feature of the design resides in a circular body having a peripheral upstanding flange and a flat bottom provided with a series of concentric circular corrugations, a horizontal circular plate of a smaller diameter than the circular body and arranged in a plane parallel thereto, said plate being provided on its upper surface with parallel rows of pointed projections, and a plurality of right-angularly-disposed intersecting webs are arranged between and connecting the circular plate with the circular body.

In the drawings, Figure 1 is a perspective view of an insect-guard embodying the herein-described design. Fig. 2 is a bottom plan view thereof. Fig. 3 is a vertical sectional

view of the guard. Fig. 4 is a detail sectional view on the line 4-4 of Fig. 3.

Referring to the drawings, the numeral 1 designates a circular cup or body having a peripheral upstanding flange 2. The circular body 1 is provided with a flat bottom having a series of concentric circular corrugations 3, and a horizontal circular plate 4 is arranged in a plane parallel with the circular body. The plate 4 is of a smaller diameter than the body 1 and is provided on its upper surface with parallel rows of pointed projections 5, and a plurality of right-angularly-disposed intersecting webs 6 are arranged between and connect the plate 4 with the body 1. The outer edges of the web 6 curve upwardly and outwardly, as at 7, toward the peripheral edge of the plate 4.

What I claim is—

The design for an insect-guard for furniture herein shown and described.

In testimony that I claim the foregoing as my own I have hereto affixed my signature in the presence of two witnesses.

JOHN CHARLIS COLLIER.
